UNITED STATES PATENT OFFICE.

AXEL ANDERSON, OF ST. PAUL, MINNESOTA, ASSIGNOR TO RUSSELL GRADER MANUFACTURING CO., OF MINNEAPOLIS, MINNESOTA, A CORPORATION.

GRADING-MACHINE.

1,248,985.

Specification of Letters Patent.

Patented Dec. 4, 1917.

Application filed September 17, 1915. Serial No. 51,261.

To all whom it may concern:

Be it known that I, AXEL ANDERSON, a citizen of the United States, resident of St. Paul, county of Ramsey, and State of Minnesota, have invented certain new and useful Improvements in Grading-Machines, of which the following is a specification.

The object of this invention is to provide means for a wider range for quickly and easily raising and lowering the forward end of the scraper blade when the same is in plowing position, permitting dipping the forward end of the blade into the ground to dig a deep and more abrupt ditch, or raising it higher in the case of cutting down high banks.

A further object of the invention is to provide means for rotatably supporting the scraper blade, permitting it to be turned to vary its angle with respect to the draft line of the machine.

Other objects of the invention will appear from the following detailed description.

The invention consists generally in various constructions and combinations hereinafter described and particularly pointed out in the claims.

In the accompanying drawings forming part of this specification,

Figure 1 is a side elevation of a grading machine embodying my invention, the blade standing substantially straight across or at right angles to the line of draft.

Fig. 2 is a longitudinal section of a forward portion of the machine.

Fig. 3 is a plan view of a portion of the machine showing particularly the circle for rotatably supporting the scraper blade, and illustrating the draft connection therefor.

Fig. 4 is a detail of the locking mechanism.

Fig. 5 is a side elevation of the machine showing the blade in working position and with its forward end dropped for the purpose of cutting a ditch.

Fig. 6 is a plan view of the machine showing the blade in substantially the same position that it occupies in Fig. 5.

In the drawings, 2 represents the frame proper of the machine having a bolster 3 at the forward end, with a forward axle 4 carrying wheels 5 and a suitable king-bolt 6.

At the rear end of the frame there is a

platform 7 for the operator, and the rear axle 8 having carrying wheels 9. I prefer to provide a curved plate 10 having a recess formed in its lower edge to receive a steel blade 11 that is secured to the plate 10 by suitable means such as a bolt 12. The plate 10 is provided with brackets 13 and 14 and said brackets 13 are pivotally connected to the lower end of hangers 15 and the brackets 14 are adjustably connected to the hangers 15 by bolts 15' which may be engaged with either one of a plurality of holes 16. This construction permits tilting the curved plate 10 and the blade 11 in respect to the hangers 15. The bolts 15' are now shown engaging the inner holes in the bracket 14. If these bolts are moved to the outer holes 16 the pressure of the earth on the blade 11 will tilt the upper edge of the curved plate 10 forward until the bolt 15' strikes the rear edge of the hanger 15. The hangers 15 are secured to a depending flange 17 of a circle or ring 18, and brace rods 19 connect the outer portions of the scraper blade with the rear portions of the ring 18 and its depending flange 17.

The horizontal portion of the ring 18 is provided on its under surface with gear teeth 20, meshing with a pinion 21 on a shaft 22 which has bearings in a stationary plate 23. A coupling rod 24 has a universal joint connection with the shaft 22 and with a post 25 that is provided with an operating wheel 26, convenient to the operator's platform 7.

Brackets 28 are preferably provided near the rear of the circle or ring 18 and a brace-bar 29 preferably extends transversely of the ring 18 and is preferably bolted to the brackets 28 at 30. The coupling rod 24 preferably passes through the bar 29 and has a loose bearing therein. When the wheel 26 is revolved power will be transmitted to pinion 21 engaging the teeth of the ring 18 and revolving the same and the scraper blade supported thereby, and changing the angle of the scraper blade with respect to the line of draft of the machine.

It will be seen that the ring 18 is of right angle form in cross section having the depending flange 17 and the horizontal main ring portion with the series of gear-teeth 20 on the under side of said horizontal portion

of the ring. Located in this position the gear teeth are protected from accidental breakage and it is impossible for dirt to collect between the teeth as would be the case if the gear teeth were on the upper surface of the ring. I also prefer to provide upon the edge of the ring a series of teeth 31. These teeth move horizontally as the ring is turned in a guiding recess 32 in the plate 23. The brackets 28 are also preferably provided with flanges extending horizontally under the teeth 31 and these flanges and the guide 32 hold the ring 18 and guide it in its circular movement. A standard 33 preferably hollow and having an inclined upper surface 36 is mounted on the plate 23 and has a guide within it for a locking bolt 34, which is adapted to enter the spaces between the teeth 31 on the ring 18 and lock the ring in any position at which it may be set. A spring 35 normally holds the pin 34 in its locking position.

A wedge-shaped plate 37 is arranged to slide on the inclined surface 36 of the standard 33 its upper edge being in engagement with a pin 38 in the upper end of the bolt 34. The forward end of the plate 37 has a beveled surface 40 on which the pin 38 rides to hold the plate and bolt 34 in their releasing position with the end of the bolt free from the teeth 31 on the ring 18. Whenever desired a grasp on the operating rod 39 will move the plate 37 lengthwise permitting the bolt 34 to be forced downward into engagement with the teeth 31 of the ring 18, thus securely locking the ring with the scraper blade at any desired angle.

I also provide the forwardly extending bars 41 rigidly secured to the brackets 28 and the plate 23, and preferably having the outwardly extending ends 42. The ends of the brace bar 29 are also preferably bolted to the outwardly turned portion 42 of the bars 41. The plate 23 is preferably provided with upwardly turned flanges to which the bars 41 are bolted at 43.

It will be observed that the bars 41, the plate 23, the brackets 28 and the brace-bar 29 together form an exceedingly rigid frame 50 of substantially triangular form upon which the circle or ring 18 carrying the scraper blade is rotatably supported.

The base of the triangle is formed by the brace bar 29 and the outwardly-turned ends 42 of the bars 41. This part of the triangular frame is toward the rear while the converging bars 41 extend forwardly and the apex of the frame is arranged preferably near but in the rear of the forward axle 3.

Links 44 are provided having their lower end pivotally connected with the ends 42 of the bars 41 and their upper ends are pivotally connected with crank arms 45 provided

ings 47 on the machine frame. These shafts are provided with worm wheels 48 and are revolved through worm gear 49 operated by suitable wheels 50 provided on each side of the machine adjacent to the platform 7. The effect of this manipulation of handwheels upon the blade is conditional, however, depending upon the lengthwise position of the blade relative to line of draft. If the blade be set square across the line of draft it is affected to the full extent of the movement of the cranks 45'. If the position of the blade be at an angle less than ninety degrees from line of draft, part of said movement of cranks 45 is consumed in a transverse tilt of the blade and consequently lost for the purpose of raising and lowering the ends of the blade. If the position of the blade be parallel to the line of draft, or nearly so, movements of cranks 45 are entirely or nearly used up in the transverse tilting of the blade, and the ends of same are not individually affected insofar as concerns raising or lowering.

The forward ends of the bars 41 constituting the part of the supporting frame for the ring or circle carrying the scraper blade converge and have secured to their forward end a segmental toothed rack 56, that is vertically arranged and has its teeth in engagement with a pinion 57 on a shaft 67. I also provide the converging draft bars 62 pivoted to the bars 41 and the plate 23 by the pivot 66. The forward ends of these bars converge and have arranged between them preferably a cast block 63 through which the king-bolt 6 passes. The bars 62 together with the block 63 form a V-shaped frame, the rear end of which is pivoted to the bars 41 and the plate 23 and the forward end of which is engaged by the king-bolt 6 upon which said frame pivots. This V-shaped frame formed by the draft bars 62 and block 63 may properly be designated a "draft frame." The shaft 67 is mounted in bearings provided at the forward ends of the draft bars 62, and formed integrally with the pinion 57 or suitably secured thereto is a worm gear 58, a worm 59 is mounted in suitable bearings and is adapted to engage the worm gear 58. The worm 59 is coupled to an operating rod 60 having an operating wheel which is within convenient reach of the operator of the machine. When the worm gear is revolved the rack 56 will be raised or lowered thereby tilting the bars 41 or causing the same to turn on the pivots 66. This tilts the frame composed of plate 23, brackets 28, brace-bar 29 and side bars 41, and has its fullest effect on the blade when the same is set parallel or nearly so to the line of draft, and loses said effect as angle of line of draft and blade increases. Movement of cog-rack 56 is, therefore, complementary to movement of cranks 45 in

producing a raise or lowering of either end of the blade regardless of what position it may have relative to line of draft.

It will be seen that the means for raising and lowering the forward end of the frame that supports the ring 18 and scraper blade is supported upon and carried by the draft frame formed of the bars 62 and the block 63.

10 The draft pole is indicated at 64, and the operating rod 65 for shifting the pole is shown mounted on a portion of the frame. This shifting mechanism, however, forms the subject-matter of an application for 15 Letters Patent filed by me June 12, 1915, Serial No. 33,711. This mechanism, therefore, needs no further description herein.

In the operation of the machine when the scraper blade is set at the usual angle of 20 about 30 degrees with respect to the draft line, the forward end of the scraper may be raised or lowered for the purpose of causing the end of the scraper blade to cut into a bank which it will do when the forward end 25 of said blade is elevated, or to cut a ditch, which it will do when the forward end of the blade is depressed. Any desired amount of elevation or depression on the forward end of the scraper blade may be secured by 30 the device herein described.

The scraper blade may be quickly reversed so that either end of the blade will be ahead and the material taken up by the scraper blade will pass along the surface of 35 that blade and be discharged at its end.

The details of the construction may be varied in many particulars without departing from my invention.

I claim, as my invention:

40 1. The combination, with a main frame and forward and rear wheeled axles upon which said frame is supported, of a longitudinally extending blade-supporting frame arranged beneath said main frame, hangers 45 located at opposite sides of the machine and supporting the rear end of said blade-supporting frame, a longitudinally extending draft frame having its rear end pivoted to said blade-supporting frame near the longitudinal center thereof, means pivotally connecting the forward end of said draft frame to the forward axle of the machine, and means upon said draft frame for raising and lowering the forward end of said blade-supporting frame, substantially as described.

2. The combination, with a main frame and forward and rear wheeled axles upon which said frame is supported, of a longitudinally extending triangular blade-supporting frame arranged beneath said main frame, hangers located at opposite sides of the machine and supporting the rear end of said blade-supporting frame, a longitudinally extending V-shaped draft frame arranged 60 outside of said blade-supporting frame and

having its rear end pivoted to said blade-supporting frame near the longitudinal center thereof, means pivotally connecting the forward end of said draft frame to the forward axle of the machine, and means upon 70 said draft frame for raising and lowering the forward end of said blade-supporting frame.

3. The combination, with a main frame and forward and rear wheeled axles upon 75 which said frame is supported, of a longitudinally extending blade-supporting frame arranged beneath said main frame, hangers located at opposite sides of the machine and supporting the rear end of said blade-supporting frame, a revolute ring secured to 80 said blade-supporting frame, a scraper blade rigidly secured to said ring, a longitudinally extending draft frame having its rear end pivoted to said blade-supporting frame near the longitudinal center thereof, means pivotally connecting the forward end of said draft frame to the forward axle of the machine, and means upon 85 said draft frame for raising and lowering the forward end of said blade-supporting frame, substantially as described.

4. The combination, with a main frame and forward and rear wheeled axles upon which said frame is supported, of a 95 longitudinally extending triangular blade-supporting frame arranged beneath said main frame, hangers located at opposite sides of the machine and carrying the rear end of said blade-supporting frame, a revolute ring secured to said blade-supporting frame, a scraper blade rigidly secured to 100 said ring, a longitudinally extending draft frame arranged outside of said blade-supporting frame and having its rear end pivoted thereto near the longitudinal center thereof, a vertical pivot connecting the forward end of said draft frame to the forward axle of the machine, and means upon said frame for raising and lowering the forward 110 end of said blade-supporting frame.

5. The combination, with a wheeled frame, of a revolute ring, a scraper blade rigidly secured to said ring, a longitudinally extending frame by which said ring is supported and guided, means for revolving said ring and the blade carried thereby on said frame, draft bars having their rear ends pivotally connected to said frame near the longitudinal center thereof and having their 115 forward ends pivotally supported upon the front axle, means for suspending the rear end of said frame, and means carried by said draft bars for raising and lowering the forward end of said frame.

6. The combination, with a wheeled frame, of a revolute ring, a scraper blade rigidly secured to said ring, a longitudinally extending blade-supporting frame to which 120 said ring is secured, means for revolv-

ing said ring and the blade carried thereby on said frame, independent means for suspending, raising and lowering each side of the rear end of said frame, a draft frame 5 having its rear end pivoted to said blade-supporting frame and its forward end pivotally connected to the forward axle of the machine, and means on said draft frame for

raising and lowering the forward end of said blade-supporting frame.

In witness whereof, I have hereunto set my hand this 24th day of August, 1915.

AXEL ANDERSON.

Witness:

ESTHER LINDSTEDT.
